Richard A. Feiss

UNITED STATES PATENT OFFICE.

RICHARD A. FEISS, OF CLEVELAND, OHIO, ASSIGNOR TO THE JOSEPH & FEISS CO., OF CLEVELAND, OHIO.

GARMENT AND METHOD OF MAKING IT.

Application filed November 13, 1922. Serial No. 600,529.

To all whom it may concern:

Be it known that, RICHARD A. FEISS, a citizen of the United States, residing at 9907 Lake Ave., Cleveland, in the State of Ohio and Cuyahoga County, have invented a new and useful Improvement in Garments and Methods of Making Them, of which the following is a specification, the principle of the invention being herein explained and the best mode in which I have contemplated applying that principle, so as to distinguish it from other inventions.

This invention relates to a garment and also to the method of making it.

My object has been to both facilitate and improve the manufacture of a garment.

Apparel, such as for instance a man's coat, customarily comprises in its breast portion an outer or forepart, an inner strip or facing overlapping as a seam the lining border, and several reenforcing fabric pieces interposed between the forepart and facing. These interposed fabrics are sewed together as laminations and are used to stiffen and hold in shape the most conspicuous section of the garment. As exemplified in the drawings the three insert pieces are canvas, hair-cloth and felt cloth respectively and they are to be additionally sewn to the facing strip so that all of the pieces of cloth inwardly adjacent to the forepart are locked together as a unit.

Heretofore, so far as I am aware, the facing has been secured to the composite stiffening insert by the lock stitch or manually effected basting stitch applied to that border of the facing which overlapped the stiffening pieces. To effect the lock stitch it was necessary to also fold the forepart back out of the way so that the lockstitches would not penetrate it, but even so the lock stitch has proven to be an inadequate securing agency because it had to be interrupted, that is to say, it would not be continuous for the full length of the section because of the pockets and the bar tracks securing the same. Basting threads are obviously a slovenly performance and because of their widely separated and loose connection must prove unsatisfactory as a permanent reliance,

They cannot bind two pieces of fabric firmly together so as to prevent relative movement of one piece along the other with attendant puckering and even creased wrinkles. Moreover, even the poor basting thread connection was omitted wherever a pocket was encountered. Such unsatisfactory results are exaggerated when the garment becomes wet or when it is afterwards improperly pressed. Manifestly, a machine stitch would be not only stronger, but could be more quickly accomplished. Supposedly, neither the parties in the trade who basted the facing and one or more reinforcing pieces together nor the parties who employed the lock stitches which were necessarily separated at a pocket have realized the possibility of using a blind stitch operation. I discovered the feasibility of and have for months successively practiced a blind stitch running the entire length of the pieces to be fastened together, without interruption at any pocket and substantially along the line where the lining overlaps the edge of the facing seam. The stitches are looped through the facing seam and composite insert from one end of the latter to the other thereby so attaching them as to make a unit with lessened tendency to lose its shape and which is more readily restored to its proper shape when distorted through moisture or hard usage.

Accordingly, I believe I have improved a garment by successfully applying an old machine stitch in a new way and a new place so that the breast portion of the garment will much longer hold its shape and specifically prevent the facing from bagging or hanging loosely and prevent the front from turning or rolling outward, thereby fulfilling a long felt want.

Adverting to the drawings:

Figure I is a plan view of the complete left forepart proper, the inner facing of the same material, a lining and a plurality of differently shaped, laminated stiffening or reenforcing pieces interposed between the enclosing pieces of fabric; the assembled parts being spread open by laying the lining down on one side and flattening all

the other parts down on the opposite side thereby disclosing the interior construction, pockets and various seams.

Figure II is a section on line II—II of Figure I.

Figure III is a section on line III—III of Figure I.

Figure IV is a section on line IV—IV of Figure I.

Figure V is a section on line V—V of Figure I.

Figure VI is a semi-diagrammatic view of the essential elements of a standard blind stitch sewing machine with relation to the various pieces of a garment which are to be sewn according to my improved method.

The disclosed section of the garment includes the outside or forepart 1, an adjacent piece of canvas 2 of less width but substantially the same length, a strip of haircloth 3 inwardly adjacent in turn to the canvas, a piece of fabric 4 in turn inwardly adjacent to the haircloth and optionally either felt or Panama cloth facing strip and lastly a lining 6. The relative positions of the parts just specified are clearly shown in Figure II. The forepart 1 is shown fashioned with a cutout 7 which conforms to the armhole and the canvas 2, and Panama or felt cloth 4 both have a bordering edge conforming to a portion of the bordering edge 7. The lining 6 is shown provided with a cutout or armhole 8 which, when flapped over will have its edge roughly conform to the edge of the cutout 7. The inside of the forepart 1 usually carries the two pockets shown, but we need concern ourselves only with the upper one which includes an outer side 9 touching the forepart and an inner side 10 against which the canvas 2 lies.

The reinforcing or stiffening units 2, 3 and 4 may be stitched together at various points by any most convenient or economical means such stitching being designated in its entirety by the reference numeral 11 because nothing is claimed for the preliminary manner of attaching those three parts. The three stiffening parts 2, 3 and 4 are of the three different shapes well shown in Figure I, the canvas 2 being defined by edges 2^a and 2^b, the haircloth by edges 3^a and 3^b and the felt or Panama cloth by edges 4^a and 4^b. The edge 2^b of the canvas will determine the line of eventual fold to produce the coat lapel 12.

The facing 5 is to have a concealed edge to form together with an overlapping edge of the lining 6, a seam 13 extending from one longitudinal end of the garment section under consideration to its other end, and crossing the upper pocket. It is this seam which has always been heretofore, so far as my knowledge extends, unsatisfactorily secured to the reinforcing inserts as ex-

plained in the preamble of this specification. For a better understanding of what my invention has proposed and made possible of successful accomplishment, attention is invited to the figures on Sheet 2.

A blind stitch machine of standard construction comprises a table top 14, a presser foot 15 and an adjustable plunger 16. Above, is a rotary shuttle 17 carrying a hook 18 and a cast-off 19. Pivotedly mounted at 20 is an oscillating needle carrier 21 provided at its lower end with a socket 22 in which a curved needle 23 is to be detachably secured. Such a needle is provided on its lower convex side with a thread holding groove terminating at the eye of the needle. One of the stitching threads 24 is to be fed through the groove in the needle 23 which after describing an arcuate path causes the thread 24 to form a loop 25 above the uppermost of the cloth pieces which are to be stitched together as is clearly shown in Figure VI. A loop locking thread 26 shown in Figures III to V inclusive is passed through the loops 25 by the shuttle 17 in a manner well known to the art so as to form the blind stitch shown in Figures III to V. It will be observed upon inspection of Figure VI that an adjustment of the plunger 16 has been made, with reference to the arcuate path to be described by the eye of the needle, which will cause the thread 24 to pass through the lining 6, the facing 5, felt or Panama cloth 4, haircloth 3 and canvas 2 in the order named, and to return through said pieces in reverse order.

I would have it distinctly understood that I make no claim to either the blind stitch machine nor to its performance of itself. I do, however, believe that I am the first to discover the commercially feasible possibility of employing a blind machine stitch to secure the lining and facing over their entire lengths either to the stiffening burlap alone at opposite ends or additionally to the haircloth and felt along a middle area at and just above the upper pocket. Thus all of the stiffening members in the breast portion are made a unit with the facing and more securely so with each other along the substantial longitudinal middle of the breast portion thereby establishing a factor of great improvement toward maintenance of the shape of the most conspicuous part of a man's coat. Moreover, the delicate adjustment which a blind stitch machine is capable of, enables the stitch to be continued even past a pocket without securing together its opposite sides 9 and 10. In Figure IV it is well shown how the loops 25 of the thread 24 enter the burlap 2 without touching the nearest pocket material 10. Besides, the machine operation is manifestly quicker and

therefore cheaper and generally more efficient and successful.

I claim:—

The method of making a garment using a plurality of laminated materials one of which carries an interjacent pocket, which consists in blind stitching together certain

of said materials on one side of said pocket continuously along a line which passes across said pocket.

Signed by me, this 11 day of October, 1922.

RICHARD A. FEISS.
